UNITED STATES PATENT OFFICE.

JAMES C. DERBY, OF CONCORD, NEW HAMPSHIRE.

DESIGN FOR A BROOCH.

43,243.

Specification for Design.

Patented Nov. 12, 1912.

Application filed September 6, 1912. Serial No. 719,037. Term of patent 7 years.

To all whom it may concern:

Be it known that I, JAMES C. DERBY, a citizen of the United States, residing at Concord, in the county of Merrimack and State of New Hampshire, have invented a new, original, and ornamental Design for Brooches, of which the following is a specification, reference being had to the accompanying drawing, forming part thereof.

The figure is a plan view of a brooch, showing my new design.

I claim:

The ornamental design for a brooch as shown.

In testimony whereof I have hereunto set my hand in presence of two subscribing witnesses, this 30th day of August 1912.

JAMES C. DERBY.
